UNITED STATES PATENT OFFICE.

BENJAMIN ROLLAND HAMMOND, OF BELOIT, WISCONSIN, ASSIGNOR TO MARY ELZADA RASMUSSEN, OF JANEVILLE, WISCONSIN.

RAILROAD SAFETY DEVICE.

1,324,893.

Specification of Letters Patent.

Patented Dec. 16, 1919.

Application filed November 30, 1917. Serial No. 204,677.

To all whom it may concern:

Be it known that I, BENJAMIN R. HAMMOND, a citizen of the United States, residing at Beloit, in the county of Rock and the State of Wisconsin, have invented certain new and useful Improvements in Railroad Safety Devices; and I do hereby declare the following to be a full, clear, and exact description of the invention, such as will enable others skilled in the art to which it appertains to make and use the same.

This invention relates to improvements in a railroad safety device and has for one of its objects the provision of a device of this character, whereby cars and the like will be prevented from jumping or disengaging from the railroad tracks.

Another object of this invention is the provision of an intermediate or third rail secured to the ties of a road bed or a railroad track and adapted to be engaged by means carried by the trucks of the cars or the like to prevent them from jumping the track and also obviating undue swaying and rocking of the cars.

A further object of this invention is the provision of a railroad safety device of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which:

Figure 1 is an end elevation partly in section of a railroad safety device constructed in accordance with my invention,

Fig. 2 is a longitudinal sectional view of the same,

Fig. 3 is a bottom plan view illustrating the means carried by the trucks for engaging the intermediate or third rail,

Fig. 4 is a plan view of the railroad track, and

Fig. 5 is a fragmentary detail sectional view of a ball bearing roller used in connection with my invention.

55

Referring in detail to the drawings, the numeral 1 indicates railroad ties which are positioned in the usual manner upon an ordinary railroad bed having secured thereto the railroad rails 2. An intermediate or third rail 3 is secured to the ties 1 between the railroad rails 2 and are in the shape of eye-beams in cross-section, including base portions 4, a web portion 5 carrying laterally projecting flanges 6 which are engaged by an attachment carried by the cars which will be hereinafter more fully described.

The numeral 7 indicates a portion of a railroad car or the like to which is connected in any desired manner a railroad truck consisting of a supporting beam 8 carrying at each end journal supporting members 9. The journal supporting members 9 have connected to their free ends journals 10 in which are rotatably mounted axles 11. The axles 11 have secured thereon ordinary car wheels 12 for engagement with the railroad rails 2. The journals 10 are of the ordinary construction in which lubricant is placed for the purpose of reducing friction.

Downwardly and inwardly extending supporting members 13 are secured to the journal supporting members 9 in close proximity to the connection of the beam 8 thereto and have secured to their inner ends 85 longitudinally extending roller supporting members 14 that are disposed in close proximity to the third or intermediate rail 3 and upon each side thereof. Ball bearing rollers 15 are journaled upon stub shafts 16 carried by each end of the roller supporting members 14 and engage the under faces of the flanges 6 upon the third or intermediate rail 3.

Vertically disposed arms 17 are carried by the stub shafts 16 and secured to journals 18 mounted on the axles 11 intermediate their ends. The arms 17 are arranged in pairs and connected by bolts 19 to which are secured braces 20. The braces 20 incline 95

upwardly and outwardly and have their outer ends secured to each side of the beam 8 as clearly illustrated in Fig. 3.

From the foregoing description taken in connection with the accompanying drawings, it will be noted when a car 7 is supplied with my improved invention, the same will be prevented from swaying or rocking and also will prevent the wheels from jumping or disengaging the rails of the railroad track.

The third or intermediate rail 3 is supported and braced to the railroad rails by hangers 21 and are only preferably applied to main railroad tracks or where the cars or the like travel at a rapid speed to prevent them from jumping the tracks and rocking or rolling thereon. The intermediate or third rail 3 at its ends has its flanges 6 pointed or reduced as illustrated at 22 so that the rollers 15 may engage and disengage when approaching or leaving the point of the track where the third or intermediate rail is used.

While I have shown and described the preferred embodiment of my invention, it will be understood that minor changes in

construction, combination and arrangement of parts may be made without departing from the spirit and scope of the invention as claimed.

Having thus described my invention, what I claim is:

A railroad safety device including a truck having a beam with an axle spaced on each side thereof carrying wheels, journals on said axles, substantially U-shaped members having their bight portions secured to the under faces of the journals and having their arms depending downwardly therefrom, a stub shaft secured to the lower end of each arm of the U-shaped members, rollers journaled to the stub shafts and arranged in pairs to engage under the flange of a guard or safety rail, braces connecting the arms to the beam and longitudinally extending rods connecting the stub axles in pairs.

In testimony whereof I affix my signature in presence of two witnesses.

BENJAMIN ROLLAND HAMMOND.
